UNITED STATES PATENT OFFICE.

ALFRED M. DEMUTH, OF CHICAGO, ILLINOIS.

SHARPENING DEVICE FOR KNIVES OF MEAT-SLICING MACHINES.

1,176,136.

Specification of Letters Patent. Patented Mar. 21, 1916.

Application filed March 17, 1915. Serial No. 14,983.

To all whom it may concern:

Be it known that I, ALFRED M. DEMUTH, a citizen of the United States, and a resident of the city of Chicago, county of Cook, and 5 State of Illinois, have invented certain new and useful Improvements in Sharpening Devices for Knives of Meat-Slicing Machines, of which the following is a specification.

My invention relates to improvements in 10 sharpening devices for the knives of meat slicing machines, and has for its object the production of a device of this character through the medium of which the circular rotary knife of a meat slicing machine may 15 be effectually sharpened with ease and expedition.

A further object is the production of a 20 sharpening device which will be of an adjustable nature permitting of its use in connection with knives of various diameters.

A still further object is the production of a sharpening device as mentioned which will be of durable and economical construction and efficient in use.

25 Other objects will appear hereinafter.

With these objects in view, the invention consists in the combinations and arrangements of parts hereinafter described and claimed.

30 The invention will be best understood by reference to the accompanying drawing forming a part of this specification, and in which—

Figure 1 is a front elevation of the upper 35 end portion of a meat slicing machine equipped with a sharpening device embodying my invention, Fig. 2 is a top plan view thereof, and Fig. 3 is an enlarged detail section taken on substantially line α — α of Fig. 2.

The preferred form of construction, as 40 illustrated in the drawing, comprises two rotary sharpening members or grinders 1 and 2, the former having a beveled periphery and 45 for engagement with the bevel at the front of the knife 3 of the machine in conjunction with which the device is employed, and the latter having a flat inner side for engagement with the rearward side of the knife, as 50 clearly shown in Fig. 2. The knife 3 is shown mounted upon a rotatable spindle 4

which is mounted in the casing or housing 5 of the machine in the usual manner.

The sharpening members 1 and 2 are rotatably mounted upon the front ends of 55 spindles 6 and 7 respectively, each of which is mounted at its rearward end in a cylindrical holder 8 which is slidably mounted in a housing 9. The housings 9 are arranged adjacent the front side of the knife 3 and are 60 supported upon the upper ends of posts 10 upon which the same are threaded. Lock nuts 11 also threaded upon said posts cooperate with the housings 9 to securely fasten the same in position. The lower ends of 65 posts 10 are mounted for vertical adjustment in laterally projecting lugs 12 formed at the upper end of a bracket 13 which arises from the machine housing 5. Set screws 14 cooperate with the posts 10 to lock the same 70 in their positions of vertical and rotary adjustment, as will be readily understood.

The sharpening members 1 and 2 are normally pressed forward by means of helical compression springs 15 which are mounted 75 in the housings 9. Each of said springs 15 encircles the reduced rearward end of the corresponding member 8, being interposed between a circumferential shoulder 16 formed upon said member 8 and the rear- 80 ward end 17 of the housing. Thus, with this arrangement, it will be seen that normally the sharpening member 1 will be pressed into contact with the front side of the knife 3, as clearly shown in Fig. 3, the member 2 85 being, however, normally held out of contact or spaced from the rearward side of said knife. At the rearward ends of spindles 6 and 7 are provided stop collars 18 which limit forward movement thereof, as will be 90 readily understood.

Cooperating with each of the sharpening members is a locking device which is provided for the purpose of locking the former in inoperative position. Each of said locking devices comprises a vertically movable plunger 19 which is mounted in a circular housing 20 arising from the corresponding housing 9. Cooperating with said plunger 19 is a helical compression spring 21 which 100 is interposed between a head 22 provided at the upper end of said housing and a col-

lar 23 which is formed adjacent the lower end of said plunger, the arrangement being such that said spring serves normally to press the plunger downwardly into engagement with the corresponding member 8. Formed in the upper side of the member 8 coöperating with each of the sharpeners is a slot 24 so positioned therein that when the corresponding sharpener is moved toward 10 inoperative position or from the slicing knife, said slot will be engaged by the corresponding plunger 19, and thus the sharpener locked in this position. With this arrangement then, it will be seen that the locking device coöperating with the sharpener 1 will serve to hold the latter against the influence of the spring 15 coöperating therewith since, when said sharpener is in inoperative or retracted position, the spring co- 15 operating therewith will be under compression. In the case of the sharpener 2, said locking device will not hold the sharpener against the influence of the spring coöperating therewith since, in this case, the sharpener will be moved to inoperative position by virtue of the spring coöperating therewith. The locking device coöperating with the sharpener 2 will therefore serve simply as a means of positively locking the same in 20 inoperative position, insuring against accidental pressing of the same into engagement with the knife.

Provided at the forward end of each of the spindles 6 and 7 is a knob or finger piece 25 whereby the former may be pressed to inoperative position and the latter manually moved against the pressure of the spring coöperating therewith to operative position, or into contact with the rearward side of the 25 knife.

In the operation of the sharpening device set forth, the sharpener 1 is first released by raising of the locking plunger 19 coöperating therewith. This having been done, 30 said sharpener will be pressed forward under the influence of the corresponding spring 15 and held by the influence of said spring in contact with the beveled or front side of the knife. In the grinding operation by the member 1 a wire edge is turned over at the outer edge of the blade and this will be removed through operation of the sharpener 2. However, care must be taken in the removal of this wire edge to prevent grinding 35 of the rearward side of the knife since this side must be maintained absolutely flat or preferably slightly concaved, as shown in Fig. 3, for the best results in the slicing operation. Therefore, in order to insure 40 against the removal of anything but the wire edge at the rearward side of the knife, the arrangement is such as will be seen, that the sharpener 2 is moved toward operative position by manual pressure and not 45 by means of a spring as in the case of sharp-

ener 1. In the operation of the sharpener 2, the locking plunger 19 coöperating therewith is first raised whereupon the corresponding finger piece or knob 25 is engaged by the fingers, and said sharpener is pressed manually toward the cutter. With this arrangement it will be seen, that delicate manipulation of said sharpener is made possible with the result that only the wire edge will be removed from the rearward side of 50 the knife in the sharpening operation.

Upon the sharpening operation being completed, the sharpener 1 may be moved to inoperative position manually through engagement with the finger piece 25 thereof, 55 said sharpener being automatically locked in retracted position by the corresponding locking member 19. Upon finger piece 25 of the sharpener 2 being released, the latter will be automatically moved to inoperative position under the influence of the corresponding spring 15 and, when said sharpener reaches its outer or inoperative position, locked in this position by the corresponding locking member 19.

Through the vertical adjustment which is afforded the posts 10, it will be seen that the sharpeners 1 and 2 may be adjusted to adapt the same for coöperation with slicing knives of various sizes. And through rotary adjustment which is afforded said posts, said sharpening devices and the holders or bearing members coöperating therewith, may be adjusted to position the sharpening members out of alinement with the knife or in 60 inoperative position in order to permit of ready removal or mounting of the knife.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and 65 modifications as come within the scope of the appended claims.

Having described my invention what I claim as new and desire to secure by Letters Patent is:

1. A device for sharpening the rotary circular knife of a slicing machine, comprising in combination a sharpener for the front of the knife; a sharpener for the back of the knife; a support for said sharpeners; means individual to said sharpeners tending normally to move said first mentioned sharpener into engagement with the knife and said second mentioned sharpener away from the knife; and means individual to 120 said sharpeners for releasably locking the same in inoperative position, substantially as described.

2. A device for sharpening the rotary circular knife of a slicing machine, comprising 125

in combination a sharpener for the front of the knife; a sharpener for the back of the knife; a support for said sharpeners; means individual to said sharpeners tending normally to move said first mentioned sharpener into engagement with the knife and said second mentioned sharpener away from the knife; and a spring pressed keeper coöperating with each sharpener for locking

the same in inoperative position, substantially as described. 10

In testimony whereof I have signed my name to this specification in the presence of two subscribing witnesses.

ALFRED M. DEMUTH.
